UNITED STATES PATENT OFFICE.

LESTER STEWART BARR AND BENJAMIN STANLEY SIMMONS, OF WASHINGTON,
DISTRICT OF COLUMBIA.

ADVERTISING DEVICE.

1,301,216.

Specification of Letters Patent. Patented Apr. 22, 1919.

Application filed May 7, 1917. Serial No. 167,010.

To all whom it may concern:

Be it known that we, LESTER STEWART BARR and BENJAMIN STANLEY SIMMONS, citizens of the United States, residing at 5 Washington, District of Columbia, have invented certain new and useful Improvements in Advertising Devices, of which the following is a specification.

This invention relates to advertising devices, and particularly to a device provided with a surface at the center upon which may be posted daily bulletins or other matter intended to attract attention, one or more marginal frames surrounding the center surface being provided with spaces to carry advertising.

The principal objects of the invention are to provide a simple, inexpensive and attractive advertising device of the above 20 character, in which the advertising matter can be easily changed.

The above and other objects and the novel features of our invention will be apparent from the following description taken in connection with the drawing which constitutes 25 a part of this application and in which,

Figure 1 is a front view of an advertising device embodying our invention.

Fig. 2 is a vertical sectional view of the 30 same taken on the line 2—2 of Fig. 1; and

Fig. 3 is a detail view taken on the line 3—3 of Fig. 1.

The advertising device may be made of wood, metal or other suitable material and 35 comprises a box-like structure consisting of the rectangular inclosing casing 10 and the bottom 11 secured to and closing the casing 10 at the rear.

A rectangular frame F consisting of the 40 top, bottom and side members 12, 13, 14 and 15 is secured to the front face of the bottom 11, centrally thereof. A rectangular space at the center of the front of the bottom is thus inclosed or surrounded on all sides and

45 this space constitutes the bulletin board B of the device upon which daily bulletins or other matter of a similar nature may be posted. The top, bottom and sides of the frame F are inclined to the plane of the bulletin board B and the ends thereof are

50 cut at an angle and fitted together to form a rectangular marginal frame around the bulletin board, resembling the molding of a picture. The inclined outer surface of 55 the frame F is designed to carry advertis-

ing matter so that persons who are attracted to read the bulletin or matter carried by the bulletin board B will be tempted to also read the advertising carried by the frame or frames surrounding the bulletin. 60

Strips 16 are secured to and extend across the top, bottom and sides of the frame F and divide the advertisement-carrying surface of the frame into spaces which may be rented to advertisers for displaying their 65 cards or advertising matter. Referring to Fig. 3 each of the strips 16 is under-cut along its longitudinal edges as at 17 and 18 to provide recesses to receive the edges of cards so that the advertising matter may 70 be readily changed from time to time. A molding 18 is secured to the outer ends of the strips 16 and extends around the outer edge of the frame F to assist in retaining the advertising cards in place and also to 75 improve the appearance of the device.

A second or outer rectangular advertising frame F' has its top, bottom and sides 121, 131, 141 and 151, respectively, overlapping and secured to the top, bottom and sides of 80 the inner frame F. The outer end of the frame F' is secured to the rectangular casing 10 and the entire frame F' is inclined to the bulletin board B and offset outwardly with respect to the inner frame F so that 85 the advertising matter or cards may be readily inserted into the recesses 17 and 18 from the front of the device. The outer frame F' is also provided with cross strips 16 having under-cut edges to provide recesses corresponding to the recesses 17 and 18 of Fig. 3. A molding 181 is secured to the outer ends of the strips 16 of the frame F' to hold the cards in the spaces formed by the cross strips. 90

The device is designed to be mounted on a wall or supported in a window to exhibit bulletins which may be changed from time to time and also to display advertising in the spaces surrounding the bulletin board. 95

While we have shown and described the device in detail, it is to be understood that numerous changes may be made therein without departing from the spirit of the invention. 100

Having thus described the invention, what is claimed and desired to be secured by Letters Patent is:

1. An advertising device comprising a bulletin board having on its front a space 110

for bulletins or advertising, a plurality of substantially rectangular frames secured to the front of said board and each entirely surrounding said space, each of said frames 5 being offset with respect to the next inner frame, the advertisement-carrying surface of said frames being inclined to the plane of said board, and strips extending across and secured to one side of each of said 10 frames to provide separate spaces on the frame for advertising cards or the like, each strip having its edges under-cut to receive the edges of the advertising cards to hold them in place.

15 2. An advertising device comprising a bulletin board having on its front a space for posting bulletins or advertising, an inner rectangular frame secured to the front of said board and entirely surrounding said

space, an outer rectangular frame secured 20 to and surrounding the inner rectangular frame, each of said frames having an advertisement-carrying surface inclined to the plane of the bulletin board, strips secured at intervals to the advertisement-carrying 25 surfaces of said frames and having under-cut edges to receive the edges of advertising matters to hold them in place, said strips dividing the advertisement-carrying surfaces into separate spaces, and the outer frame 30 being offset with respect to the inner frame to permit the insertion and removal of advertising cards into or from the spaces of the inner frame.

In testimony whereof we affix our signatures.

LESTER STEWART BARR.
BENJAMIN STANLEY SIMMONS.
